United States Patent Office

Des. 197,402
Patented Jan. 28, 1964

197,402

AUTOMOBILE

Stewart A. Burnside, Philadelphia, Joseph L. de Pedroso, Jr., Haverford, Anthony S. Lawinski, Philadelphia, and Henry W. Wessells III, Paoli, Pa., and Erwin B. Kolt, Birmingham, Mich., assignors to The Budd Company, Philadelphia, Pa., a corporation of Pennsylvania

Filed Apr. 24, 1963, Ser. No. 74,595

Term of patent 14 years

(Cl. D14—3)

Fig. 1

Fig. 2

Fig. 3

Fig. 4

FIG. 1 is a top view of an automobile embodying our new design;

FIG. 2 is a side elevation of the automobile shown in FIG. 1;

FIG. 3 is a fragmentary perspective view of the front end of the automobile shown in FIGS. 1 and 2;

FIG. 4 is a fragmentary perspective view of the rear end of the automobile shown in FIGS. 1 and 2.

The dominant features of our design reside in the portions shown in full lines.

We claim:

The ornamental design for an automobile, substantially as shown and described.
